DEVICE FOR CONTROLLING VERTICALLY
SLIDING WINDOWS

William Young, Wishaw, Scotland

Application August 22, 1938, Serial No. 226,167
In Great Britain August 30, 1937

5 Claims. (Cl. 16—200)

This invention relates to devices for controlling vertically sliding windows and more particularly applicable to those mounted on vehicle bodies.

Various types of such device have been proposed, the object of which is to make the window easily slideable up and down without any effort to the operator and at the same time will maintain the window in any position without moving due to rattling, shaking or other vibration of the said vehicle. Such devices are not always successful in keeping the window in the desired position, and further, many of them need effort to push them in one direction or the other and the pressure which is needed to operate them is not constant over the whole range. Further, such devices are often complicated and expensive to produce and one of the objects of the present invention is to devise a simple and cheap device in which the pressure at all times to move the window will be constant over substantially the whole travel both up and down and in which the window will remain "put" in any position so that it will not move from the position in which it is left.

Another object of the invention is to provide a self balancing window in which the lever arms are provided with cam surfaces engaging with a yoke or slipper member which is pressed against them by means of compression springs housed in a spring box.

Another object of the invention is to provide a self balancing window which will stay in any position and which will not be inclined to move due to jolts, bumps or other movement of the vehicle on which it is mounted.

The invention will now be described, by way of example, as applied to the door of a vehicle, with reference to the accompanying drawings in which—

Figure 1 is a front elevation of the device with a portion removed.

Figure 2 is a side view of Figure 1.

Figure 3 is a section on the line 3—3 of Figure 1, with the springs removed.

Figure 4 is a detail.

Figure 5 shows a handle for operating the window.

Figure 6 shows a window having a slight swinging movement, and

Figure 7 shows a window having a slight horizontal movement.

According to one form of the invention illustrated in Figures 1, 2 and 3 of the drawings, a spring box A is provided which comprises two thin metal plates B,B, which are stamped out so

that they form when put together three tubular cylindrically shaped casings C¹C²C³ situated side by side, the two plates being secured together by suitable rivets or pins D. At the top of the spring box the plates are spaced apart a sufficient distance to form a slot E to allow two lever arms F,F to be pivotally mounted therebetween. These two lever arms F,F are pivoted about separate points G¹G² at the top of the spring box, by suitable pins or the like. The two lever arms are provided with cam-shaped members or surfaces H,H made integral therewith, which cams are adapted to engage a slipper or yoke member J mounted loosely between the two said plates B,B of the spring box. The yoke member J is pressed up against the two cams on the lever arms by means of three helical springs K¹K²K³ situated one in each of the said tubular casings C¹C²C³ so that the free ends of the arms F,F are pressed upwards and will tend to come together. The yoke member J is provided with two depending projections J¹J² which enter the springs K¹K³ to locate it centrally and prevent it from moving sideways. If desired, a projection for each spring may be provided. The space or slot E between the two plates B,B is made sufficiently long to permit of up and down movement of the yoke member J and movement of the lever arms F,F.

At the bottom of the spring box A a suitable cross-piece L is provided which engages the bottom of the three springs K¹K²K³, and this is pressed up towards the springs by means of a setscrew M so that the tension of the said springs against the yoke member may be altered to suit circumstances. The setscrew M engages in a U-shaped member or setscrew support N which is tapped or threaded for the purpose and is secured to the ends of the two plates B,B of the spring box by rivets O or the like. A lock nut M¹ is provided on the setscrew M if required. The U-shaped member or setscrew support N may contain a nut or the like instead of being tapped or threaded and it may be made integral with the spring box, if desired.

The spring box is secured to the non-movable part of the window-frame or to the door of a vehicle, for instance, in which the window slides by screws or any other suitable means passing through holes Q in the plates B,B. The two free ends of the lever arms are each provided with a roller or pin P which slides or rolls in a slot S in a member T mounted on the bottom channel of the movable part of the window R. The pins may rotate in the slots at the same time as they slide along when the window is raised up and

down. The window R is provided with a suitable knob or projection U upon the glass or the frame in which the glass is contained, if such is used, so that the window may be pressed up and down. The cams H are so formed or shaped that a constant pressure or force is given by the springs K through the lever arms to the window throughout its travel. If desired, however, by suitably shaping the cams, the pressure or force on the window when it is close to the top of its travel, say the last half inch of its travel, may be increased so as to ensure closing of the window under all circumstances, but the pressure remains constant over all the rest of the travel. In this manner, the window may be moved up and down very easily and will remain "put" in any position. The cams will always be sliding over the surface of the yoke member when any movement takes place and the friction between these parts is sufficient to prevent the device from moving of its own accord.

Instead of having three tubular cylindrical casings for three springs, one or more springs may be employed with the appropriate number of casings according to the size of the window and the space available. By having three small diameter springs instead of one, the diameter of the springs is considerably reduced and the thickness of the device is made a minimum so that it takes up only a very small amount of room in the door or other part of the body in which it is fitted, resulting in additional seating room being provided. If desired, the springs instead of being helical may be made of any other suitable shape such as zigzag or they may be leaf springs or the like.

The ends of the two lever arms are provided with teeth V so that they will move in unison and consequently windows which are unstable in position by reason of their shape, or are not guided at each side, can be successfully moved up and down without jamming. If, however, the device is to be applied to windows which are stable or are guided at each side, then said teeth on the lever arms may be dispensed with, as the window itself will keep the arms moving in unison.

The cams on the lever arms, if desired, may be provided with notches Z or flats shown in Figure 4, with which the yoke member J will co-operate so as to create catching or stopping places in the movement of the window at any pre-arranged positions and such positions will be obvious to the feel when the said window is raised up and down.

Instead of having a projection on the window or its framing to operate the closing and opening thereof, winding means may be employed. For example, a rotatable handle W (Figure 5) may be mounted upon part of the body, door or the like in which the window slides, or on the spring box having a gear wheel engaging with the teeth V upon the ends of the lever arms F so as to raise or lower the window by the rotation of the said handle in the usual manner, the amount of movement of the handle being governed by the size of the gear.

The spring box A itself, instead of being rigidly secured to the door or other part of the body in which the window is mounted may be pivotally secured thereto at the point X as shown in Figure 6, such that the whole window itself may pivot about this point in its own vertical plane. In order to permit this to take place, the slot in which the window slides on one side or the other is preferably extended sideways so that the window may swing into the extension of the slot

taking up the position shown in chain dotted lines in Figure 6, and thereby provide a small vertical opening I, which will permit a limited amount of ventilation without actually lowering the window. Sometimes it is an advantage to have the vertical opening instead of a horizontal opening, as it may have more effect in extracting air from the inside without causing draughts.

Alternatively, in order to permit the window to move to create this vertical opening I, the window may bodily slide horizontally along the rollers P in the slot S as shown in Figure 7 into a suitable slot or the like provided at the side of the window frame, to take up the position shown in chain dotted lines in Figure 7. This will also give a slight vertical opening for ventilation purposes. A suitable handle or knob U¹ is provided for moving the window horizontally.

The bottom of the extension of the slot in which the window slides may be curved or sloped into the other part of the guide as shown at Y so that when the window is open with a slight vertical opening and downward pressure is applied thereto, the curved portion of the slot in which the window slides will pull the window back again to its normal horizontal position so that it will then descend in the normal manner without having necessarily to perform the double movement of sliding the window sideways and then pressing it downwards. In the case of the whole window pivoting about the point on the spring box, the window can also be pressed downwards, even when there is a vertical opening, and will then function in the normal manner. Or, if desired, it can be swung about the horizontal pivot point first, before being opened.

It is to be understood that the cross-piece which is used for adjusting the tension of the springs may be dispensed with and no adjustment may be provided in certain cases.

Further, for narrow windows, one lever arm of the device may be dispensed with and the springs will then be so situated that either one or more press directly through a suitable thrust piece or slipper on to the cam member and the yoke member common to the two cams is then unnecessary. Such a lever device is very suitable for narrow windows, when there is no room to house the two arms.

The device is more particularly designed for mass production and all the parts are preferably stamped out and put together by riveting or other means, but may be made in any other way, if desired.

It is to be understood that although the device is described as being attached to the bottom rail of the window for windows opening downwards it may be connected to the top rail for windows opening upwards and further that various alterations in details from those described may be made without departing from the scope of the invention.

I claim:

1. In a device for counterbalancing vertically slidable windows, a spring box, at least one lever arm one end of which is pivotally mounted upon said spring box and the other end adapted to contact with said window, a cam shaped surface provided upon said lever arm, a slipper member mounted in said spring box so as to reciprocate in a straight line, and compression springs mounted in said spring box to press said slipper member against said cam surface so that it slides over the said slipper member.

2. In a device for counterbalancing vertically

slidable windows the combination comprising a spring box, a pair of lever arms pivotally mounted at one end in the spring box and adapted to make contact with the said window at the other

5 end, a cam shaped surface provided upon each of the said lever arms, a slipper member mounted in said spring box so as to reciprocate in a straight line, and compression springs mounted in said spring box to press said slipper member 10 against said cam surfaces so that they slide over the said slipper member.

3. In a device for counterbalancing vertically slidable windows the combination comprising a spring box, a pair of lever arms pivotally mounted 15 at one end in the spring box and adapted to make contact with the said window at the other end, gear teeth on the pivoted ends of said lever arms engaging one another causing the said arms to move in unison, a cam shaped surface provided 20 upon the portion of each of the said lever arms adjacent to said gear teeth, a slipper member mounted in said spring box so as to reciprocate in a straight line, and compression springs mounted in said spring box to press said slipper member 25 against said cam surfaces so that they slide over the said slipper member.

4. In a device for counterbalancing vertically slidable windows the combination comprising a

spring box, a pair of lever arms pivotally mounted at one end in the spring box and adapted to make contact with the said window at the other end, a cam shaped surface provided upon each of the said lever arms, a slipper member mounted in 5 said spring box so as to reciprocate in a straight line, a plurality of tubular casings in said spring box, and a compression spring located in each tubular casing, said compression springs pressing said slipper member against said cam surfaces. 10

5. In a device for counterbalancing vertically slidable windows the combination comprising a spring box, a pair of lever arms pivotally mounted at one end in the spring box and adapted to make contact with the said window at the other end, 15 gear teeth on the pivoted ends of said lever arms engaging one another causing the said arms to move in unison, a cam shaped surface provided upon the portion of each of the said lever arms adjacent said gear teeth, a slipper member 20 mounted in said spring box so as to reciprocate in a straight line, a plurality of tubular casings in said spring box, and a compression spring located in each tubular casing, said compression springs pressing said slipper member against said 25 cam surfaces.

WILLIAM YOUNG.
